UNITED STATES PATENT OFFICE.

DAVID C. DAVIS, OF SWISSVALE, PENNSYLVANIA, ASSIGNOR TO WESTINGHOUSE ELECTRIC AND MANUFACTURING COMPANY, A CORPORATION OF PENNSYLVANIA.

ELECTRODE-COOLING SYSTEM.

1,159,903.

Specification of Letters Patent.

Patented Nov. 9, 1915.

Application filed January 23, 1915. Serial No. 3,971.

To all whom it may concern:

Be it known that I, DAVID C. DAVIS, a citizen of the United States, and a resident of Swissvale, in the county of Allegheny and State of Pennsylvania, have invented a new and useful Improvement in Electrode-Cooling Systems, of which the following is a specification.

My invention relates to cooling systems for vapor rectifiers and like apparatus, and it has for its object to provide means whereby the temperatures of various portions of said apparatus may be maintained at definite predetermined values with respect to each other.

In the accompanying drawing, Figure 1 is a side view, partially in section and partially in elevation, of a mercury-arc-vapor rectifier embodying my invention; and Figure 2 is a side view, partially in section and partially in elevation, of a detail modification thereof.

In the operation of vapor rectifiers, especially those of large size and of the metal-container type, the amount of heat generated at the anodes is so great as to cause rapid deterioration of the substance thereof, with the expulsion of occluded gases and instability in the operation of the arc. In order, therefore, to maintain the temperature of the anodes within reasonable limits, it has become a usual practice to artificially cool them as, for example, by a stream of cooling fluid flowing through the interiors thereof.

In an application of Frank Conrad, Serial No. 705,037, filed June 21, 1912, and assigned to the Westinghouse Electric & Manufacturing Company, is disclosed a rectifier-cooling system of this type wherein a stream of cooling fluid, after passing through a cathode-cooling space, is divided into branches which flow through the separate anodes and then reunite. On account of the exceedingly small frictional hydrostatic head developed in each branch of this multiple fluid path, it is difficult to obtain a proper division of cooling fluid between the different branches thereof. The slightest structural dissimilarity between two anodes

may give rise to a substantial difference in 50 the relative amounts of cooling fluid passing through them, with consequent erratic and inefficient action of the rectifier.

In an application of L. M. Aspinwall, Serial No. 3972, filed Jan. 23, 1915, and assigned to the Westinghouse Electric & Manufacturing Company, is disclosed a rectifier cooling system which is an improvement upon the above, in that a stream of cooling fluid is passed through the anodes in succession whereby exactly equal amounts of cooling fluid are supplied to the anodes in equal periods of time. This system is very effective in many cases but I have found that operation of the successive anodes in the 65 cooling stream at higher and higher temperatures, because of the gradual increase in the temperature of the cooling fluid tends to preclude extremely close regulation of the temperature of the various portions of the 70 rectifier as required, for example, when it is necessary to operate at or nearly the maximum possible efficiency. For example, I

have found that, when employing a two-anode rectifier, the anodes may be maintained at equal temperatures by using a cooling system of the Aspinwall type and by diverting a small portion of the cooling fluid around the heated surfaces of the first anode. In this manner, the first anode is provided 80 with a small amount of cooling fluid of low temperature and the second anode is provided with a larger amount of cooling fluid of relatively high temperature. It is well known that the rate of dissipation of heat 85 varies directly as the difference in temperature between the heat-dissipating and heat-receiving bodies. Accordingly, by proper adjustment of the apparatus, I am enabled to remove from the first anode as many calories per unit of time by the use of a relatively small amount of cooling fluid and a relatively high temperature difference as are removed from the second anode per unit of time by the use of a large amount of cooling 90 fluid and a relatively small difference of temperature.

Referring to the accompanying drawing,

2 is the container of a rectifier, preferably of the mercury-vapor-arc type, provided with a liquid cathode 3 and with suitable metallic anodes 4 and 4', preferably of hollow steel. 5 Current is supplied to the anodes 4 and 4' by suitable conductors 5 and flows from the cathode through a suitable conductor 6. The cathode 3 may be maintained in an active condition by any suitable means, such, for 10 example, as a keep-alive circuit shown diagrammatically at 7. The container 2 is surrounded by a jacket 8 of such size that there is provided an annular cooling space 9 around the cathode 3. Suitable tubes 10 and 15 10' project into the interiors of the hollow anodes 4 and 4' and are open at their lower ends for a purpose to be hereinafter described. Cooling fluid from any suitable source is supplied to the space 9 through a 20 tube 11 and thence flows via a tube 12 to the interior of the left hand anode 4, through the tube 10, and impinges upon the active heating surface thereof. The cooling fluid then passes through the annular space between 25 the tube 10 and the neck of the anode 4 and through a suitable tube 13 and the tube 10' to the active heating surface of the anode 4'. It is thence conducted through the annular space between the tube 10' and 30 the neck of the anode 4' to a suitable overflow tube 14. Suitable insulating joints 15 are placed in the tubes 12, 13 and 14 in order to prevent short circuiting of the rectifiers. A suitable by-pass tube 16 connects 35 the tube 12 with the tube 13, and the passage of fluid therethrough is controlled by a suitable valve 17. By the manipulation of the valve 17, a greater or less amount of cooling fluid may be diverted from the anode 4 and 40 thus the anode 4 will be supplied with a relatively small amount of cooling fluid at a comparatively low temperature. On the other hand, since no by-pass is provided around the cooling space of the anode 4', all 45 of the cooling fluid, at a relatively high temperature, passes therethrough. By a suitable adjustment of the valve 17, the two anodes may be maintained at substantially equal temperatures in spite of the increment 50 of the temperature of the cooling fluid in each anode.

In the form of my invention shown in Fig. 2, I have illustrated a modification wherein an anode 4, provided with a cooling tube 10 in the interior thereof, carries an adjustable baffle member 20 surrounding the lower end of the cooling tube. The baffle member may be raised or lowered by any suitable means such, for example, as a rod 55 60 18 projecting from the apparatus.

In operation, a portion of the cooling fluid impinges directly upon the hot end of the anode, as shown by arrows 19, and a portion thereof passes up inside the baffle member 20

and hence does not come into contact with 65 the heated surfaces. By employing a baffle member of this character, I am able to dispense with the by-pass 16 and the valve 17 and still obtain equally effective action.

While I have described my invention as 70 applied to the two main anodes of a vapor rectifier, it is obvious that it may be applied to electrodes of other kinds, such, for example, as keep-alive anodes, either in connection with each other or in connection with 75 the main anodes, and, furthermore, it is readily applicable to other types of apparatus, such, for example, as X-ray tubes.

While I have described and illustrated a preferred embodiment of my invention, I do 80 not desire to be restricted thereto, but desire that only such restrictions shall be placed upon my invention as are set forth in the appended claims or are imposed by the prior art.

85

I claim as my invention:

1. In vapor electric apparatus, the combination with a plurality of anodes, each of which is provided with a cooling space, of means for cooling both of said anodes by a 90 single stream of cooling fluid, and means for equalizing the cooling effects of the stream in the two anodes.

2. In vapor electric apparatus, the combination with a plurality of anodes, each of which is provided with a cooling space, of means for cooling both of said anodes in succession by a single stream of cooling fluid, and means for equalizing the cooling 95 effects of the stream in the two anodes. 100

3. In a vapor electric apparatus, the combination with a plurality of anodes, each of which is provided with a cooling space, of means for maintaining said anodes at substantially the same temperature comprising 105 a stream of cooling fluid, means for directing a portion only of said cooling fluid upon the heated portions of one anode, and means for thereafter directing a greater portion of said cooling fluid upon the heated portions 110 of the second anode.

4. In vapor electric apparatus, the combination with a cathode and a plurality of anodes, each of said electrodes being provided with a cooling space adjacent thereto, of means for passing a stream of cooling fluid through the cathode-cooling space and then through each of the anode-cooling spaces in succession, and means for equalizing the cooling effects of said stream upon 115 120 said anodes.

5. The method of artificially cooling a plurality of heat-generating units to substantially the same temperature, said units generating heat at substantially equal rates, 125 which comprises passing a stream of cooling fluid to each of said units in succession, diverting a portion of said cooling fluid around

the heat-dissipating surfaces of the first unit, and diverting smaller and smaller portions of said cooling fluid around the heat-dissipating surfaces in each of the succeeding units.

In testimony whereof, I have hereunto

subscribed my name this 18th day of Jan. 1915.
